UNITED STATES PATENT OFFICE.

CHARLES E. VAN NORMAN, OF SPRINGFIELD, MASSACHUSETTS.

COVERED FASTENING DEVICE.

SPECIFICATION forming part of Letters Patent No. 536,164, dated March 19, 1895.

Application filed November 21, 1894. Serial No. 529,528. (No model.)

To all whom it may concern:

Be it known that I, CHARLES E. VAN NORMAN, of Springfield, in the county of Hampden and State of Massachusetts, have invented a new and useful Improvement in Covered Fastening Devices, of which the following is a specification, reference being had to the accompanying drawings, in which—

Figure 1 is a top-plan view, and Fig. 2 a side view of one form of fastening device, namely, an eyelet, embodying my invention, on a greatly enlarged scale, and without the covering, for the sake of greater clearness. Fig. 3 is a central vertical section of the eyelet shown in Figs. 1 and 2 with the covering. Fig. 4 is an enlarged view, in cross-section, of an eyelet and covering dies, this view particularly illustrating the function of the flange feet with which fastening devices embodying my invention are provided. Fig. 5 shows my invention embodied in a lacing stud, and Fig. 6 shows it embodied in a button.

My invention relates to a great variety of fastening devices and parts thereof that are covered in whole or in part with various compounds, such as celluloid or rubber, for example; and the objects of my invention are to facilitate the manufacture of these covered fasteners and to secure an improved product.

My invention consists, broadly, in a fastener-body formed with a flange having, on its under side, feet which are within the perimeter of the flange; and also, broadly, in the combination of a fastener-body of said character with a cover of any desired compound.

A minor feature of my invention lies in slitting the body, so that the compound on the outside of the flange is united with the compound on the inside of the fastener-body by portions of the compound lying in the slits, these bonds of union between the outside and inside deposits of covering compound being within the perimeter of the covered article.

In the drawings, showing my invention in the best form now known to me, 1 is a fastener-body, by which term I mean, any article or thing to be covered, in whole or in part, with a covering compound; and 2 is a flange on both sides of which the covering compound is placed.

In the course of manufacturing fastening

devices of this class, I have discovered that in order to facilitate the manufacture and to turn out a more durable product, it is necessary to have the under side of flange 2 some distance above the supporting die (see D, Fig. 4) when the plastic cover 3 is pressed on by the facing-die (see D', Fig. 4) because the pressure exerted by the facing die tends to force the under surface of flange 2 against the face of the supporting die, and limit or prevent the composition from getting well under and against the under surface of the flange. By means of the feet 4 from the under face of flange 2, the under face of flange 2 is kept at a proper practical height above the face of the supporting die (see Fig. 4), during the homing of the facing die, to allow a proper flow of the compound under and against the under face of flange 2. I have also discovered that in order to secure the strongest and most enduring hold of the plastic or like covering compound on body 1, it is necessary to preserve the integrity of flange 2, that is, to keep the flange intact along its outer edge 5, and, at all points, above the face of the supporting die; or in other words, the edge 5 of the flange projects beyond the feet, as at 6, so that the compound may fill in under the flange and between the feet. For this reason the feet are projections from the under side of the flange, within the perimeter of the flange, so that the compound may fill in between the feet and underneath the whole edge 5 of the flange. I preferably slit the feet, as at 7, so that the covering compound within and without the flange may be united or bonded together by portions of the compound in and through the slits, as at 8; but this is a minor feature of my invention, although the bonding is important in that it tends to insure the permanency of the covering.

What I claim is—

1. As a new article of manufacture, a fastener-body formed with a continuous flange which has supporting feet projecting from its under side within the perimeter of the flange, substantially as and for the purpose set forth.

2. As a new article of manufacture, a fastener-body formed with a flange which has supporting feet projecting from its under side within the perimeter of the flange, the edge of the flange projecting beyond the bases of

the feet, substantially as and for the purpose set forth.

3. As a new article of manufacture, a fastener-body formed with a flange which has 5 perforated supporting feet projecting from its under side, within the perimeter of the flange, substantially as and for the purpose set forth.

4. As a new article of manufacture, a fastener or fastener member, comprising a body formed with a flange having supporting feet projecting from its under side within its perimeter, combined with a plastic covering within and without the flange and holding on the flange between the feet, substantially as 15 and for the purpose set forth.

5. As a new article of manufacture, a fastener or fastener member, comprising a body formed with a flange and with supporting feet from the flange within the perimeter of the

flange, the edge of the flange projecting beyond the bases of the feet, combined with a plastic covering within and without the flange and holding on the flange between the feet, and on the portion of the flange which projects beyond the bases of the feet, substantially as and for the purpose set forth.

6. As a new article of manufacture, a fastener or fastener member, comprising a body formed with a flange and perforated feet dependent from the flange within the perimeter thereof combined with a plastic cover within and without the flange and through said perforations, substantially as and for the purpose set forth.

CHARLES E. VAN NORMAN.
